MULTI-GAP COLD-CATHODE ELECTRIC DISCHARGE TUBES AND THEIR USE FOR COUNTING AND LIKE PURPOSES

Bloomfield James Warman, Charlton, London, England, assignor to Siemens Brothers & Co. Limited, London, England, a British company

Application March 7, 1955, Serial No. 492,552

13 Claims. (Cl. 315—84.6)

This invention relates to multi-gap cold-cathode gas-filled electric discharge tubes and their use for counting and like purposes.

In the case of a known type of multi-gap cold-cathode electric discharge tube, a plurality of electrodes are arranged so as to form a series of electronically-coupled discharge gaps or paths, and the current fed to the gaps is of such a value that a discharge can be maintained over only one gap at any time. A discharge across one gap causes the gas in adjacent gaps to become ionised, the intensity of ionisation of the adjacent gaps falling off as their distance from the discharging gap is increased, so that the gaps immediately adjacent either side of a discharging gap can themselves be brought to a discharging condition more readily than any of the other gaps in the tube.

In the case of one specific known form of counting tube of the type referred to, several separate cathode electrodes are arranged in a circle about a common anode electrode, and two equally spaced guide electrodes are provided between each pair of cathodes. The guide electrodes immediately adjacent one side of each cathode are commoned to one guide lead and the guide electrodes immediately adjacent the other side of each cathode are commoned to another guide lead. A priming electrode is placed in close relationship to one of the cathodes, and the counting action is brought about by causing a discharge to be established first between the priming electrode and the associated cathode and subsequently between this cathode and the common anode and then applying voltage pulses of suitable magnitude to the two guide leads in turn, thus causing the discharge to be transferred from this cathode to the next, in steps over the two intervening guide electrodes, the direction of transfer depending on the order in which the voltage pulses are applied to the guide leads. Since each cathode electrode is connected to a separate external connecting wire, the value of any number which the tube may have counted can be indicated electrically at any time to other apparatus, and consequently tubes of this form have a wide field of application.

The present invention arises from the realisation that in many applications of counting devices the need to indicate electrically the value of a number counted does not arise since utilisation of the numbers counted into the device may be brought about simply by counting the numbers out of the device. This is particularly the case in telephone exchange systems where it is often necessary to store a dialled digit and subsequently to control the setting of a switching device in accordance with its value. In such applications, after a digit has been counted into the counting device, the control of the apparatus to be set may be effected simultaneously with the counting out of the digit, the only external indication from the counting device required being a signal to indicate that the counting out has been completed.

One object of the present invention is the provision of a multi-gap cold-cathode electric discharge tube which

2

is of economical construction and which is particularly adapted to the registration and utilisation of digits by counting the value of the digit into the tube and subsequently counting the same digital value out again.

Another object of the invention is the provision of a multi-gap cold-cathode electric discharge tube which is adapted to register a plurality of digital values whereby a single cold-cathode electric discharge tube may serve for the storage and subsequent utilisation of a number of successively dialled digits in a telephone exchange switching system.

According to one main feature of the present invention, there is provided a multi-gap cold-cathode electric discharge tube, having main anode and cathode electrodes and subsidiary guide electrodes, in which one of the main electrodes is of helical form while the other is of linear form and lies suitably spaced from the helical electrode with its axis parallel to the axis of the helical electrode, and in which the guide electrodes are associated with one of the main electrodes in such a way that a glow discharge between the main electrodes is caused to move along the helix in response to the application of counting stimuli to appropriate electrodes of the tube.

According to another main feature of the invention, a multi-gap cold-cathode electric discharge tube, comprising anode, cathode and guide electrodes, has an anode electrode wound in the form of a continuous helix, and has at least one group of cathode electrodes comprising a main and two guide cathodes all of linear, rod-like form, these cathode electrodes being suitably spaced from and regularly disposed around the anode helix with their axes lying parallel to the axis of the helix.

According to yet another main feature of the invention, a multi-gap cold-cathode electric discharge tube, comprising anode, cathode and guide electrodes, has a cathode electrode wound in the form of a continuous helix, and has at least one group of anode electrodes comprising a main and two guide anodes all of linear, rod-like form, these anode electrodes being suitably spaced from and regularly disposed around the cathode helix with their axes lying parallel to the axis of the helix.

Cold-cathode electric discharge tubes arranged in accordance with either of the last-mentioned two features and with suitable potentials applied to the main anode and cathode electrodes, may be operated by the application of successive stimuli to the guide electrodes, such stimuli causing the glow discharge to move in steps round the turns of the helical electrode. As many linear electrode groups as required may be situated around the helical electrode, the greater the number of such groups provided the smaller being the deflection per step due to the counting stimuli.

According to a further main feature of the invention, a multi-gap cold cathode electric discharge tube, comprising anode and cathode and guide electrodes, has its cathode and the guide electrodes in the form of a multi-wire helix wound in the manner of a multi-start screw thread, the helix being disposed in spaced relation to an anode or anode assembly in such a way that discharge gaps are formed between the anode or anode assembly and points on the helix opposite said anode or assembly. Cold cathode electric discharge tubes arranged in accordance with this feature and with suitable potentials applied to the main anodes (which may be of linear or rod-like form) may be operated by the application of successive stimuli to the guide electrodes. In this case, however, the application of such stimuli causes the discharge to move in steps from turn to turn of the helix.

According to yet another feature of the invention a multi-gap cold cathode electric discharge tube comprising anode and cathode and guide electrodes has its cathode and the guide electrodes in the form of a multi-wire helix

wound in the manner of a multi-start screw thread and a plurality of anodes of linear form lying parallel with the axis of the helix and spaced therefrom to provide discharge gaps with the wires of the helix, each of the anodes forming with the helical cathode and guide electrodes which it faces an independent counting section of the tube whereby the values of a number of successively received digits may be counted and stored. With a cold cathode electric discharge tube arranged according to this feature the value of a received digit may conveniently be registered as the number of helical turns on the cathode helix separating the glow discharges between the cathode and two of the anodes. Registration in this manner can be effected by arranging that a glow discharge is stepped along one counting section of the tube in response to the impulses of a received digit and that a further glow discharge is initiated at the start of another counting section of the tube prior to the receipt of a following digit. The glow discharge marking the end of any one digit may also mark the beginning of the next digit, the impulses of each digit advancing all the existing glow discharges along the main helix in step with their spacings preserved. An advantage of this arrangement is that it automatically forms the digital values registered into a queue along the length of the helix and so permits their utilisation in the order of receipt without the need for any distributors to couple the linear electrodes in a particular order to the utilisation equipment. With this method of counting receiving distribution means are required to control the initiation of the glow discharges in the various counting sections of the tube as digits are received.

According to still another feature of the invention receiving distribution means as referred to above are provided within the tube itself and comprise a digit counting helix which is continuous with the main and guide helices in the counting part of the tube but the guide electrodes in the distribution part of the tube are electrically separate from the guide electrodes in the counting part of the tube, signals applied to the guide electrodes in the distribution part of the tube causing the glow discharges in that part of the tube to advance one turn along the main helix so that one of the discharges appears at the commencement of the counting part of the tube.

The previously mentioned and other features of the invention are exemplified in the specific embodiments now to be described with reference to the accompanying drawings.

Different embodiments of the invention will now be described by way of example with reference to the accompanying drawings. In the drawings Fig. 1 shows diagrammatically a gas-filled multi-gap cold cathode electric discharge tube with a helical cathode and rod-like anode and guide electrodes and Fig. 1A is a diagrammatic cross-sectional view of the tube of Fig. 1 along the line A—A. Fig. 2 shows schematically a circuit arrangement for use with a tube as illustrated in Fig. 1. Fig. 3 shows a cold cathode tube with a rod-like anode and helical cathode and guide electrodes. Fig. 4 shows diagrammatically a cold cathode tube with a plurality of rod-like anodes and helical cathode and guide electrodes and Fig. 4A is a diagrammatic cross-sectional view of the tube of Fig. 4 along the line B—B. Fig. 5 shows schematically a circuit arrangement for use with a tube as illustrated in Fig. 4. Fig. 6 shows diagrammatically a cold cathode tube similar to that shown in Fig. 4 but in which receiving distribution means are provided within the tube itself and Fig. 7 shows schematically a circuit arrangement for use with a tube as illustrated in Fig. 6. The tubes with electrodes arranged as illustrated in Figs. 1, 1A, 4, 4A and 6 will have the electrodes connected to lead-in wires sealed into the tube at one or both ends in a manner similar to that illustrated in Fig. 3.

Reference should now be had to Figs. 1 and 1A. The tube comprises an envelope 1, preferably of glass into which are sealed leads to the several electrodes and in

which is supported a former 2 of insulating material, suitably glass, on which the helical cathode 3 is wound. The former may be cylindrical with a helical groove in its surface to accommodate the wire of the cathode. Spaced from the surface of the helical cathode are three other electrodes, the anode 4, and two anodic guide electrodes 5 and 6. The anode and the guide electrodes are stiff wires or rods which may be self-supporting or anchored to the wall of the tube, lying parallel to the axis of the helix. The spacing of these electrodes is equiangular with respect to the axis of the helix and the spacing from the surface of the helix such as to provide gaps across which glow discharges may be set up, the length of the gaps being determined inter alia by the pressure of the gas filling of the tube, and the voltages to be applied to the electrodes. The tube is filled with an inert gas or a mixture of gases. The helical cathode is severed so as to form two parts, a main cathode 7 and an output cathode 8, the latter being formed by an end turn of the helix which is severed at 9 from the remainder. If the tube is to be used as a decade counter the main cathode 7 would consist of 10 turns of the helix.

Fig. 2 shows circuit connections that may be employed for the operation of the tube of Fig. 1 as a counting device. In Fig. 2 the electrodes of the tube bear the same designations as in Figs. 1 and 1A but their representation is diagrammatic. There are also shown condensers C1 and C2 and reversing contacts RV connected to the guide electrodes 5 and 6 and resistances connected to the several electrodes of the tube (except the anode thereof). The tube electrodes are connected as follows. The main cathode 7 is connected over load resistance R3, contacts SC and current limiting resistance R4 to earth and the output cathode is connected over resistance R5 and the current limiting resistance R4 to earth and also over condenser C3 to wire UC leading to a utilisation circuit which would be a circuit in which use is made of the impulses stored in the tube and subsequently counted out. The anode 4 is connected over contacts AC directly to a source of positive potential indicated as a positive battery with its negative pole earthed and the anodic guide electrodes 5 and 6 are connected over resistances R1 and R2 respectively to a similar or the same source of positive potential. The guide electrodes 5 and 6 are also connected over reversing contacts RV and condensers C1 and C2 respectively to wires P1 and P2 to which impulses may be applied. The contacts RV may conveniently be contacts of a relay to be operated when, after impulses have been stored it is required to count them out. For the purpose of operating the tube the anode is connected to the source of positive potential, for example by closure of contacts AC, whereupon a glow discharge will be set up between the anode 4 and the cathode 8. To commence counting, contacts SC are closed and impulses are fed to the guide electrodes over wires P1 and P2. Each impulse to be counted gives rise to pulses on these wires as follows, first a positive pulse on wire P1 and a negative pulse on wire P2 followed by a negative pulse on wire P1 and a positive pulse on wire P2. The first negative pulse is fed to electrode 6 and the first positive pulse is fed to electrode 5 resulting in an increase in positive potential on electrode 5 and a decrease in potential on electrode 6. The area of maximum glow discharge is shifted along the cathode 7 from the main anode 4 to the anodic guide electrode 5. The following pulse of reversed polarity results in an increase in positive potential on electrode 6 and a decrease in potential on electrode 5 and the glow discharge is shifted from the anodic guide electrode 5 to the anodic guide electrode 6. Upon the termination of the pulse the potentials on the guide electrodes revert to their normal values which are below that of the anode so that the glow discharge is now shifted from the anodic guide electrode 6 to the main anode 4. As a result of the receipt of pulses representing a single impulse to be counted the

glow discharge has moved round the cathode helix, in a clockwise manner looking at the lower end of the tube of Fig. 1, from the cathode 8 to the first turn on cathode 7 and one impulse will have been counted. Further impulses are counted in a similar manner and cause the glow discharge to travel round the helix from one turn facing the anode to the next until at the end of the impulsive discharge appears between the turn on cathode 7 corresponding to the number of impulses counted and the anode 4. To count out the impulses the reversing contacts RV are operated and further sets of pulses are fed over wire P1 and P2 and at the same time impulses are delivered to the utilisation circuit. This time, owing to the operation of contacts RV the pulses to the guide electrodes are fed in the opposite order so that the first negative pulse on wire P2 reduces the potential of the anodic guide electrode 5 and the first positive pulse on wire P1 increases the potential of the anodic guide electrode 6 thereby causing the area of maximum glow discharge to shift along the cathode from the main anode 4 to the anodic guide electrode 6 and the cathode, i. e. in counter-clockwise direction looking at the lower end of the tube of Fig. 1. The following increase of potential on electrode 5 and decrease of potential on electrode 6 will cause the discharge to shift from electrode 6 to electrode 5 and when the pulse ceases, to the anode 4 whereupon the discharge will appear between the anode 4 and one turn on the cathode 7 nearer the cathode 8 and one impulse will have been counted out. The same result may be had without the reversing contacts by arranging for the pulses to be fed to the wires P1 and P2 in the reverse order, that is to say a negative pulse first appears on wire P1 and a positive pulse on wire P2 followed by a positive pulse on wire P1 and a negative pulse on wire P2. Continued feeding of pulses to the wires P1 and P2 and to the utilisation circuit will shift the glow discharges backwards, with respect to the counting-in direction, until a discharge is caused to appear on cathode 8 in consequence of which a signal will be transmitted over condenser C3 and wire UC to the utilisation circuit to stop further impulse transmission and to terminate the counting out process.

In an alternative form of the tube shown in Fig. 1 the anode may be formed as a helix with a separate output electrode at one end and the cathode and guide electrodes may be of rod-like form. In such an arrangement the guide electrodes would be cathodic instead of anodic as in Fig. 2.

In the arrangements so far described the operation of the tube may be arranged to be of a cyclic nature by arranging a separate or priming electrode at the upper end (in Fig. 1) of the tube and providing separate means to accept a signal from the output electrode and to feed a corresponding pulse to the priming electrode to cause the discharge to transfer immediately to the priming electrode in readiness for continued counting action. Reference will now be had to the multi-gap tube shown in Fig. 3. In this figure the tube 1 is shown broken to indicate a greater length than that actually shown. Corresponding parts have been given the same designations as in Figs. 1 and 1A. The cathode is a helix shown in thick lines with its left hand turn severed at 9 from the remainder to form a single turn output cathode 8 separate from the multi-turn main cathode 7 but forming a continuation of the helix. The guide electrodes 5 and 6 are also helices wound on former 2 with the cathode helix to provide a multi-wire helix in the manner of a three-start screw thread so that the turns of the helices appear from left to right as output cathode 8, guide electrode 5, guide electrode 6, main cathode 7, guide electrode 5 and so on. The guide electrodes in this embodiment are cathodic. The anode 4 is a stiff wire lying parallel with the axis of the multi-start helix and supported by metal members embracing the former 2 on which the helix is wound and suitably spaced from the surface of the helix to form gaps

with the wires of the helix. In the tube shown the anode 4, cathode 7 and guide electrode 6 are connected to lead-in wires sealed into a pinch at the right hand end of the tube and the cathode 8 and guide electrode 5 are connected to lead-in wires and sealed into a pinch at the left hand end of the tube. The number of turns on the main cathode will be determined by the number of impulses to be counted. For the operation of the tube pulses are applied to the guide electrodes in such a manner that for each impulse to be counted a negative pulse is applied to electrode 5 and a positive pulse to electrode 6 followed by a positive pulse to electrode 5 and a negative pulse to electrode 6 to cause a glow discharge to transfer from a cathode turn first to the adjacent turn of electrode 5 and then to the adjacent turn of electrode 6 and when the pulses cease the discharge is caused to transfer from the turn of electrode 6 to the adjacent cathode turn. An initial discharge is first set up by a pulse fed to the output cathode 8 from which it is transferred to turns on the main cathode 7 as described above and appears finally when a digit has been counted, between the anode and the cathode turns corresponding to the number of impulses counted. Counting out is performed in a similar manner to that described in connection with the tube of Fig. 1, pulses being fed to the guide electrodes in the reverse order to that for counting in to cause the discharge to be transferred back to the output cathode. Simultaneously with the pulses fed to the guide electrodes impulses are fed to the utilisation circuit connected to the output cathode and the return of the discharge to the output cathode gives a signal to the utilisation circuit to stop further impulse transmission and to terminate the counting out process.

A modification of the tube shown in Fig. 3 will now be described with reference to Figs. 4 and 4A. In these figures, which are diagrammatic, the tube is provided with a cathode helix comprising a main cathode 7 and an output cathode 8, helical guide electrodes 5 and 6 wound with the cathode helix in the manner of a three start screw thread, the whole forming a multi-wire helix, and a plurality of anodes in the present example five in number. There is also an independent priming cathode. The anodes are designated 41, 42, 43, 44 and 45 and are in the form of stiff rods spaced about the axis of the helix and at a suitable radial distance from the surface of the helix to form discharge gaps therewith. The cathode helix is shown in thick lines and beyond, that is to the left of the output cathode 8, is a home turn 10 forming a continuation of the helix but separated from the output cathode 8. The turn 10 is connected internally or externally with the main cathode 7. The priming cathode 11 which is at the opposite end of the tube to the output cathode is in the form of a ring or disc from which fingers 12 project towards the ends of the anode rods forming gaps therewith. It is to be understood that the several electrodes within the tube are connected to lead-in wires suitably sealed into the tube which is preferably of glass. The electrode arrangement shown is suitable for a tube to count and store the impulses of four digits and for this purpose there would be 43 turns of the cathode helix and 42 turns of each of the guide electrode helices to cater for digits on a decimal basis as ordinarily used in telephone systems. Each anode together with the cathodic helices forms in effect a separate counting section. The operation of the tube is started by applying a suitable potential to a selected anode and simultaneously feeding a negative pulse to the priming cathode to cause a discharge to take place between that cathode and the selected anode, the other anodes inactive at the time. Consequent on the appearance of a discharge between the priming cathode and an anode, potential change in the priming circuit causes the discharge to transfer from the priming cathode to the first turn of the main cathode 7. Once an anode is supporting a glow discharge to the main cathode the anode voltage

is so reduced that the negative pulse to the priming cathode is insufficient for this anode to strike another glow discharge to the priming cathode. Impulses to be counted give rise to pulses on the electrodes 5 and 6 as earlier described and the discharge set up is transferred along the helix until when all the impulses of a digit have been counted the discharge appears between the selected anode and the turn on the cathode 7 corresponding to the number of impulses counted. At the end of a digit external circuit arrangements effect the selection of another anode and give rise to a pulse to be fed to the priming cathode to start a new discharge between the first main cathode turn and the newly selected anode. Further impulses to be counted cause pulses to be fed to the guide electrodes as previously mentioned with the result that the discharge representing the digit now being counted is advanced along the helix together with those representing previously stored digits. When the impulses of all the digits to be counted have been stored a number of discharges equal to one more than the number of digits will be present between the several anodes and the cathode, their spacing along the turns of the cathode corresponding to the number of impulses they represent. For the counting out of the stored impulses locally generated impulses give rise to positive and negative pulses which are fed to the guide electrodes and all the discharges are advanced along the tube towards the output cathode. At the same time impulses are fed to the utilisation circuit connected to the output cathode. When a discharge arrives at the output cathode it transmits a signal to the utilisation circuit that counting of a digit has ended and brings about circuit changes for the counting of the following digit. A discharge having reached the output cathode it is transferred by the action of the guide electrodes to the home turn where it remains. The circuit associated with the home turn is such that a plurality of discharges may be maintained between this turn and the several anodes.

Circuit arrangements suitable for operating the tube of Fig. 4 as a four digit counter are schematically illustrated in Fig. 5 to which reference should now be had. In this figure the electrodes are given the same designations as in Figs. 4 and 4A. As will be seen from the figure each anode is connected over a load resistance to a source of positive potential shown as a battery with its negative pole earthed and to a point on a distributor D. The distributor may take any known form and may operate electronically to count digits. It has a number of sections, one more than the number of digits to be counted, each section being connected to a different anode; section D1 being connected to anode 41, section D2 to anode 42 and so on. Anode 41 is shown connected to the source of positive potential over resistance R41. The main cathode 7 is connected to earth and the output cathode 3 is connected over a resistance R4 to earth and over condenser C3 to wire UC leading to the utilisation circuit. The priming cathode 11 is connected over resistance R11 to earth and over condenser C4 and wire NP to a source of negative pulses in a signal generator ED. The guide electrodes 5 and 6 are connected to a device IS which applies successive pulses of opposite polarities to the guide electrodes in response to each impulse received over wire IMP also in response to each impulse received over wire LS from a source of locally generated impulses. Impulses received over wire IMP are also transmitted to a signal generator ED which operates in the manner of the well known dialling relay associated with an electromechanical selecting switch in a telephone system. Immediately prior to the receipt of a train of impulses to be counted it receives a signal over wire DS to bring about the removal of earth potential from the anode associated with that section of the distributor that is connected up at the time and at the same time to transmit a negative pulse over wire NP to the priming cathode 11. At the end of an impulse train the signal generator ED

transmits a pulse to the distributor to connect up the next section. In the normal condition of the circuits illustrated all the anodes 41-45 are maintained at earth potential and the section D1 of the distributor D is connected up. When the circuits are taken into use a signal is received over wire DS to remove the earth potential from anode 41 connected up by section D1 of the distributor and at the same time a negative pulse is fed to the priming cathode 11 and a discharge is initiated between cathode 11 and anode 41. On the termination of the pulse the discharge transfers to the first turn on main cathode 7. When dialled impulses are fed over wire IMP to device IS successive positive and negative pulses for each impulse are fed to the guide electrodes to transfer the discharge initially set up on the first turn of helix 7 to a turn corresponding to the number of impulses to be counted. The impulses over wire IMP are also received in the signal generator ED. At the end of the first impulse train a pulse is transmitted from signal generator ED to the distributor to connect up section D2 and prior to the receipt of a second impulse train a signal over wire DS brings about the removal of earth potential from anode 42 now connected up by section D2 of the distributor and at the same time a negative pulse is fed to the priming cathode 11 to initiate a discharge between that cathode and anode 42 which is transferred from cathode 11 to the first turn on cathode 7 as before. The successive positive and negative pulses for each impulse of the second train are fed to the guide electrodes and the discharge between anode 41 and the main cathode 7 together with the discharge between anode 42 and the main cathode 7 are advanced along the cathode helix as many turns as there are impulses in the train to be counted. At the end of the second impulse train a pulse is transmitted from the signal generator ED to the distributor to connect up section D3 whereupon anode 43 becomes connected up. Subsequent impulse trains set up discharges between other anodes and the main cathode and all the discharges in the tube are advanced along the cathode helix as before, the anodes being rendered active in turn and a discharge initiated prior to the commencement of each impulse train and the distributor being stepped on after the end of each impulse train received. At the end of the fourth impulse train there will be four discharges between points on the main cathode and anodes 41-44 respectively and a fifth discharge is set up between anode 45 and the first turn of the main cathode. The spacing between the several discharges along the main cathode will correspond to the impulses in each of the four digits counted.

For the counting out of the impulses, impulses are fed to device IS over wire LS and at the same time to the utilisation circuit connected to the output cathode. The impulses received by device IS cause successive pulses to be applied to the guide electrodes and all the discharges are advanced along the cathode turns towards the output cathode. As each discharge appears on the output cathode it gives rise to a signal to the utilisation circuit that counting of a digit is to cease and that counting of the next digit is to commence. Discharges appearing on the output cathode are transferred by the action of the guide electrodes to the home turn where, by reason of a direct connection to earth of this turn a plurality of discharges between this turn and the several anodes 65 may be sustained. When the last digit has been counted battery potential is removed from the devices IS, ED and D which thereupon assume their normal condition and earth potential is re-applied to all the anodes and the tube is extinguished.

Fig. 6 shows a multi-gap cold-cathode tube similar to that of Fig. 4 for operating as a four digit counter. The tube is longer than that of Fig. 4 and includes at its right hand end an electronic distributor. The main cathode 7 is similar to that of Fig. 4 but it includes four additional turns. The tube may be considered as com-

prising two parts, a counting part and a distributor part, the latter being the right hand end and including the four additional cathode turns. Between the cathode turn in the counting part of the tube which commences at the fifth cathode turn designated 71 and extends to include the home turn 10 are the guide electrodes 5 and 6 wound as helices with the cathode turns in the manner of a three-start screw thread to form a multi-wire helix and the first four turns of the cathode are wound with two other wires 13 and 14 and herein referred to as distributor guide electrodes to form another multi-wire helix, the electrodes 13 and 14 being separate from the guide electrodes 5 and 6. There are five rod-like anodes 41-45 which extend throughout the counting part of the tube four of the anodes extending for different distances into the distributor part of the tube. Thus, anode 41 terminates opposite the 5th cathode turn, anode 42 terminates opposite the 4th cathode turn and so on. There is also a priming cathode 11 as in Fig. 4 but with fingers 12 extending for different lengths to form priming gaps with the ends of the several anodes. In response to a negative pulse fed to the priming cathode discharges appear at all the priming gaps and on the termination of the pulse transfer to the turns of the main cathode opposite the ends of the respective anodes. As before, each anode together with the cathodic electrodes forms a counting section. Discharges between anode and cathode are transferred by action of the guide electrodes as in the previous example. The impulses of the first digit will effect transfer of the discharge between anode 41 and cathode turn 71 to a point along the main cathode corresponding to the number of impulses received. At the end of the impulse train successive pulses will be fed to the distributor guide electrodes to transfer the discharges on the first four cathode turns one turn forward, bringing the discharge on anode 42 to turn 71. The impulses of the second digit are advanced along the cathode and at the same time the discharge representing the first digit is correspondingly advanced. At the end of this and of each successive digit the discharges in the distributor part of the tube are advanced one cathode turn and the impulses of each digit transfer the discharge appearing on cathode 71 together with previously set up discharges in the counting part of the tube along the main cathode until the impulses of the last digit have been counted and stored. When this occurs there will be five discharges present, four discharges between different turns in the main cathode and the several anodes and one between turns 71 and anode 45, the spacing between the several discharges along the main cathode corresponding to the impulses in the several digits counted. The stored impulses are counted out exactly as described in connection with the preceding example.

Circuit arrangements suitable for operating the tube of Fig. 6 are shown in Fig. 7. In general, these are similar to those of Fig. 5 but earth potentials are not applied to the anodes and removed from them in turn as all the anodes are active when the tube is taken into use. As in Fig. 5 the anodes are connected over load resistance such as resistance R41 to a source of positive potential, main cathode 7 is connected to earth, output cathode 8 is connected over resistance R4 to earth and over condenser C3 and wire UC to a utilisation circuit and priming cathode 11 is connected over condenser C4 and wire NP to which negative pulses may be applied and also over resistance R11 to earth. The devices IS and LS are similar to the device IS in Fig. 5 and device ED generates successive positive and negative pulses at the end of each impulse train received by it over wire IMP. Device IS generates successive positive and negative pulses in response to impulses to be counted received over wire IMP and device LS generates similar pulses from a source of locally generated impulses. It is to be understood that change over arrangements will connect the guide electrodes 5 and

6 either to device IS or LS as required. When the tube is taken into use a negative priming pulse is fed over wire NP to the priming cathode 11 and discharges are set up between this cathode and the ends of each anode. When the priming pulse terminates these discharges transfer to the turns of the main cathode adjacent the ends of the respective anodes, the discharge on anode 41 appearing on cathode turn 71 and the discharges on the other anodes appearing on cathode turns 4, 3, 2 and 1. The first impulse train to be counted is transmitted over wire IMP to the device IS which, as before described delivers successive positive and negative pulses at each received impulse to the guide electrodes 5 and 6 to cause the discharge on anode 41 to advance along the counting part of the tube. At the end of the impulse train successive positive and negative pulses are transmitted from the device ED to distributor guide electrodes 13 and 14 to cause the discharge on the first four cathode turns to advance one cathode turn so that the discharge on anode 42 now appears on cathode turn 71 and the discharges on the anodes 43-45 appear on the 4th, 3rd and 2nd cathode turns respectively. The impulses of the second impulse train give rise to the pulses on guide electrodes 5 and 6 to advance the first and second discharges between their respective anodes and the turns of cathode 7 so that the spacing between the first and second discharges corresponds to the number of pulses in the first received impulse train. At the end of the impulse train device ED feeds pulses to the distributor guide electrodes 13 and 14 to advance the discharges on the 4th, 3rd and 2nd turns to the 5th, 4th and 3rd turns respectively. Successive impulse trains are counted in a similar manner to that described for the first and second trains, all the discharges moving along the tube between their respective anodes and the cathode 7, the discharges in the distributor part of the tube being advanced one cathode turn at the end of each impulse train. At the end of the fourth impulse train there will be spaced discharges between the cathode 7 and anodes 41-44 and a discharge between cathode turn 71 and anode 45. For the utilisation of the counted impulses, pulses derived from locally generated impulses in the circuit LS are delivered to the guide electrodes 5 and 6 and the discharges are transferred along the tube towards the output cathode where they give rise to a signal over wire UC to indicate the end of a digit and are then transferred to the home turn as described in connection with Fig. 5.

What is claimed is:

1. A gas-filled multi-gap cold cathode electric discharge tube having main anode and cathode electrodes one of which electrodes is in the form of a helix and the other of which is of linear form lying parallel with the axis of the helix and spaced therefrom to form discharge gaps with the surface of the helix and guide electrodes arranged to provide discharge gaps with one of said main electrodes and positioned so that on the application to them of stimuli a discharge between the main electrodes will move along the helical electrode.
2. A gas-filled multi-gap cold cathode electric discharge tube having a helical cathode, an anode and guide electrodes all of linear form and lying parallel with the axis of the cathode helix and spaced therefrom equiangularly with respect to said axis to provide discharge gaps with the cathode helix, the guide electrodes being so positioned that on the application to them of stimuli a discharge between the anode and cathode will move round the helix along the tube in a unidirectional manner.
3. A gas-filled multi-gap cold cathode electric discharge tube having a helical anode, a cathode and guide electrodes all of linear form and lying parallel with the axis of the anode helix and spaced therefrom equiangularly with respect to said axis to provide discharge gaps with the anode helix, the guide electrodes being so positioned that on the application to them of stimuli a discharge

between the anode and cathode will move round the helix along the tube in a unidirectional manner.

4. A gas-filled multi-gap cold cathode electric discharge tube having helical cathodic electrodes arranged in the manner of a multi-start screw thread and an anode of linear form lying parallel with the axis of the helical electrodes and spaced therefrom to provide discharge gaps with the surfaces of the helices, one of the helical electrodes being a main cathode and the other helical electrodes being guide electrodes for causing a discharge between the anode and the main cathode helix to move along the helix in a unidirectional manner from one main cathode turn to the next under the influence of stimuli applied to the said guide electrodes.

5. A gas-filled multi-gap cold cathode electric discharge tube for the counting and storing of impulses of a plurality of digits having helical cathodic electrodes arranged in the manner of a multi-start screw thread and a plurality of anodes in number one more than the number of digits to be stored and of linear form lying parallel with the axis of the helical electrodes and spaced therefrom with respect to the said axis to provide discharge gaps with the surfaces of the helices, one of the helical electrodes being a main cathode and the other helical electrodes being guide electrodes for causing a discharge between the main cathode helix and an anode to move along the helix in a unidirectional manner from one main cathode turn to the next under the influence of stimuli applied to the said guide electrodes.

6. A gas-filled multi-gap cold cathode electric discharge tube for the counting and storing of impulses of a plurality of digits having helical cathodic electrodes arranged in the manner of a multi-start screw thread one helical electrode being a main cathode and the other helical electrodes being guide electrodes for causing a discharge between the main cathode helix and an anode to move along the helix in a unidirectional manner under the influence of stimuli applied to the guide electrodes and a plurality of anodes in number one more than the number of digits to be stored and of linear form lying parallel with the axis of the helical electrodes and spaced with respect to said axis to provide discharge gaps with the surfaces of the helices, said tube comprising a counting part and a distributor part, the main cathode extending throughout both parts and the said guide electrodes extending only throughout the counting part, further helical guide electrodes also forming with the main cathode helix a multi-wire helix arranged in the manner of a multi-start screw thread of equal diameters extending only throughout the distributor part of the tube the number of turns of the main cathode helix in the distributor part of the tube corresponding to the number of digits to be stored by the tube, the anodes extending throughout the counting part of the tube and into the distributor part for varying distances such that each anode terminates opposite a different turn of the main cathode.

7. A gas-filled multi-gap cold cathode electric discharge tube according to claim 1 in which the helical electrode comprises a number of turns forming a main helix and a single turn at one end thereof being a continuation of the main helix but separated from it to form an output electrode.

8. A gas-filled multi-gap cold cathode electric discharge tube according to claim 5 in which the main cathode helix comprises a number of turns forming a main helix and two turns at one end thereof being a continuation of the main helix but separated from it and from one another, the turn nearer the main helix forming an output cathode and the turn more remote from the main helix being connected in a circuit that will sustain a plurality of discharges between said more remote turn and the anodes.

9. A gas-filled multi-gap cold cathode electric discharge tube according to claim 5 in which at the end of

the tube adjacent that end of the helix at which a discharge is to be initiated is a priming cathode of circular form co-axial with the helix and with projections extending into the tube and opposing the ends of the anodes.

10. A gas-filled multi-gap cold cathode electric discharge tube for the counting and storing of impulses having a cathode in the form of a helix, an anode of linear form lying parallel with the axis of the helix and spaced therefrom to form discharge gaps with the surface of the helix and guide electrodes and means for setting up an initial discharge between the anode and one end turn of the helix, means for feeding pulses to the guide electrodes in one order of succession to transfer said initial discharge to a turn on the helix corresponding to the number of impulses to be counted and stored and means for feeding pulses to the guide electrodes in the opposite order of succession to transfer the discharge from the turn to which it was brought by said first mentioned pulses back to said end turn.

11. A gas-filled multi-gap cold cathode electric discharge tube for the counting and storing of impulses provided with electrodes according to claim 10 in which the helix comprises a number of turns forming a main helix and at one end thereof a single turn forming a continuation of the main helix but separated from it comprising an output electrode connected to a utilisation circuit and in which during the feeding of pulses to the guide electrodes in said opposite direction impulses are fed in step with said pulses to the guide electrodes and the return of the discharge to said end turn provides a signal to the utilisation circuit that counting is to cease.

12. A gas-filled multi-gap cold cathode electric discharge tube for the counting and storing of impulses of each of a plurality of digits provided with electrodes according to claim 5 in which the cathode helix comprises a number of turns forming a main helix and at one end thereof a single turn forming a continuation of the main helix but separated therefrom comprising an output cathode to which is connected a utilisation circuit and means for setting up at the commencement of each digit to be counted a discharge between the main helix and a selected one of the anodes, means operative at the end of each digit for selecting the anodes in turn and means for feeding pulses to the guide electrodes to transfer discharges between the main helix and the several anodes to positions along the main helix corresponding to the impulses in each digit to be counted and means for feeding further pulses to the guide electrodes and at the same time feeding impulses to the utilisation circuit to transfer all the discharges to said output cathode, the arrival of a discharge on said output cathode giving rise to a signal to the utilisation circuit that counting of the digit represented by the discharge is to cease.

13. A gas-filled multi-gap cold cathode electric discharge tube for the counting and storing of impulses of each of a plurality of digits provided with electrodes according to claim 6 in which the cathode helix comprises a number of turns forming a main helix and at one end thereof a single turn forming a continuation of the main helix but separated therefrom comprising an output cathode to which is connected a utilisation circuit and means for setting up initial discharges between turns of the main helix and adjacent ends of the several anodes in the distributor part of the tube and a discharge between the first turn in the counting part of the tube and the adjacent end of an anode and means for feeding pulses to the guide electrodes in the counting part of the tube to transfer discharges therein along the main helix to positions corresponding to the impulses to be counted and means operative at the end of each digit for feeding pulses to the guide electrodes in the distributor part of the tube to advance the discharges in that part of the tube to the next main helical turn nearer the counting part of the tube and means for feeding pulses

to the guide electrodes in the counting part of the tube and for feeding impulses in step therewith to the utilisation circuit to transfer all the discharges to the output cathode, the arrival of a discharge on the output cathode giving rise to a signal to the utilisation circuit that counting of the digit represented by that discharge is to cease.
